(57) **CLAIM**

The ornamental design for a surgical device, as shown and described.

DESCRIPTION

FIG. 1 is a side view of a surgical device showing my new design;

FIG. 2 is a front view thereof;

FIG. 3 is a bottom plan view thereof;

FIG. 4 is a top plan view thereof;

FIG. 5 is a rear view thereof; and,

FIG. 6 is a perspective view thereof.

The broken lines shown represent unclaimed subject matter that form no part of the claimed design.

1 Claim, 4 Drawing Sheets
